UNITED STATES PATENT OFFICE.

ISAIAH G. MACFARLANE, OF WILKINSBURG, PENNSYLVANIA.

IMPROVEMENT IN RAILWAY CARS.

Specification forming part of Letters Patent No. 125,969, dated April 23, 1872.

SPECIFICATION.

To all whom may it concern:

Be it known that I, ISAIAH GRAHAM MACFARLANE, of Wilkinsburg, in the county of Allegheny and State of Pennsylvania, have invented a new and useful Improvement in Railroad Car; and I do hereby declare the following to be a full, clear, and exact description thereof, reference being had to the accompanying drawing forming a part of this specification, in which—

Figure 1 is perspective view, partly broken away, of my improved car-body. Fig. 2 is a vertical cross-section of the same through xx , Fig. 1, and Fig. 3 is a longitudinal vertical section of the same.

Like letters of reference indicate like parts in each.

My invention relates to that class of railroad freight-cars which may be used either for dumping or shoveling, and by the peculiar construction of which, as hereinafter described, I obtain both these desired results, together with the requisite strength and durability.

To enable others skilled in the art to make and use my improvement, I will describe its construction and use.

The frame-work of the car consists, first, of the bottom rails aa , which run from end to end near the center, and carry the bumpers a' at their extremities; second, of the bolsters cc , which extend across just under the ends of the body D , and are secured to the bottom rails aa by bolts, and, by means of the bolster-stakes c^1 and braces c^2 , aid in sustaining the side rails e ; third, of the side rails e , which extend along the side of the car, and are connected together at their ends by the cross-ties f ; and, fourth, of the braces g , which extend diagonally upward from the point of conjunction between the bottom rails aa and bolsters cc to the point of conjunction between the bolster-stakes c^1 c^1 and side rails ee , and aid in supporting the side rails ee . The braces g operate to transfer much of the weight which, in cars of the ordinary construction, bears almost entirely upon the ends of the bolsters, to the bottom rails aa at the center of the car, and, in connection with the rods l and n , hereinafter described, sustain the ends of the bolsters cc . The frame is further strengthened by the iron rods k k , which extend, one on each side

of the car, along the rails a from the bumpers a' a' , over the braces g g , and under the cross-tie k ; by the rods ll , which extend across the car from the bolster-stakes c^1 through the braces g g and bottom rails aa ; and by the rods nn , which extend from the top of the side rails down along the sides of the bolster-stakes c^1 c^1 to the bolsters cc . Extending across the center of the body D is a girder, m , which strengthens the center of the car. The cross-ties f are sustained by the posts f' f' , which rest upon the bottom rails aa . The body D is hopper-shaped, and is formed by nailing or otherwise fastening the boards or metal plates composing the sides d and ends d^1 to the bottom rails aa and side rails ee and cross-ties ff . The sides may be extended vertically above the side rails ee , as at d^2 , and downward at the bottom, as shown at d^3 , if desired. Hinged to the lower edge of the bottom rails aa , on the exterior of the body, are two pairs of trap-doors, hh , which, when closed, form the bottom of the car. These doors open downward, and are held shut by the support or cross-bar h' , which is hinged to one bottom rail, a , on one side, and is held or supported by the hook i , extending down from the other bottom rail a on the opposite side. When the support-bar h' is disengaged from the hook i , and allowed to drop, the trap-doors hh open, and permit the contents of the car to come or drop through the open bottom. The devices constitute my arrangement for dumping. Heretofore in cars of this kind, having "dumping"-doors in the bottom, the doors have been secured by means of a link and pin, a chain connected with a ratchet and pawl, or other like device, placed inside of the car. Such devices are very frequently damaged by the freight in the car, while they interfere with the operation of dumping and shoveling. The interior of my car-body is entirely free from machinery, so that I avoid all these difficulties. In each of the inclined ends of the body D I make a door, o , which is hinged at its inner end, o' , and opens downward. When open, the door is supported by the stringers p , which extend inward from the bumpers a' until they reach the inclined ends d^1 d^1 . In front of the door o , hinged to the rails aa , is a movable platform, p' , which, when the door o is open, is thrown out, as shown at p^2 , so as to project beyond the end of the rails aa , and afford a

place to stand upon for convenience in shoveling. When the door *o* is closed, the platform is turned in, and rests upon the stringers *p*, as shown at *p*³. The space between the posts *f* and the inclined ends *d*¹ is closed up by boards, so as to limit the passage from the end of the car to or nearly to the width of the door *o*.

If it is desired to shovel from the car coal, sand, or freight of like nature, the platform *p*¹ is thrown out to the position shown at *p*², and the door *o* opened. Then the operator, standing on the platform *p*¹, is enabled to shovel from the car with ease. The door *o* is fastened in any convenient way, as, for instance, by a link and pin, as shown at *r*.

This car is not only adapted to carrying coal, sand, and other material of like nature, but to carrying freight of many other kinds. By opening both doors *o*, it may be used for carrying railroad rails and bar-iron. When used for freight of smaller bulk, as barrels, &c., the car may be loaded and unloaded through the doors *o*. Among the advantages arising from the peculiar construction of my car is, is that the interior of the body *d* is entirely free from machinery, so that the handling of the freight is not interfered with, and the car does not easily get out of order. Also, in dumping, the contents of the car are emptied in the center of the track, and do not fall upon and clog up the rails; and, as the incline of the sides and

ends is steep, the entire contents of the car are emptied without difficulty. In shoveling coal it is impossible to work to advantage unless the shovel can be inserted under the coal on the bottom of the car. This I am enabled to do by means of the doors *o*, which, opening downward, lie under the coal, and afford an opening to the bottom of the car.

What I claim as my invention, and desire to secure by Letters Patent, is—

1. In the construction of railroad cars, the braces *g*, in combination with the bottom rails *aa* and side rails *ee*, substantially as described.

2. The braces *g* and rods *ll*, in combination with the side rails *ee*, bottom rails *aa*, and bolster *c*, substantially as and for the purposes described.

3. The end doors *o*, arranged and operating substantially as described, so as to form a platform for shoveling and loading and unloading the car *d*.

4. The movable platform *p*¹, in combination with the door *o*, substantially as and for the purposes described.

In testimony whereof I, the said ISAIAH GRAHAM MACFARLANE, have hereunto set my hand.

ISAIAH G. MACFARLANE.
